TROLLEY CONTACTOR

Frank H. Richterkessing, Louisville, Ky., assignor to Cheatham Electric Switching Device Co., Incorporated, Louisville, Ky., a corporation of Kentucky

Application January 11, 1941, Serial No. 374,033

2 Claims. (Cl. 246—252)

My invention relates to a trolley wire contactor for the purpose of controlling the operation of auxiliary electric railway devices, such as electrically operated track and/or trolley frog switches, signal apparatus, such as lights, bells, and crossing gates, when engaged by a current collector carried by a passing vehicle.

One object of this invention is to provide a contactor of simple sturdy construction primarily for use in mines, especially where only a minimum of space between the trolley wire and ceiling is available. Obviously the principles and structure disclosed herein have uses in other branches of the electric railway industry.

Another object of this invention is to provide a contactor that can be installed at practically any location without disturbing the trolley wire, that is, a contactor that can be attached to any straight section of trolley wire by the simple process of clamping the end brackets of the contactor to the wire. Additional support can be provided by attachment to a ceiling hanger or a span wire.

A further object of this invention is to provide an improved and simplified type of contactor structure embodying some of the principles disclosed in U. S. Patent No. 1,569,039 to Richard R. Scroggan.

The above objects of this invention are accomplished by the new and novel construction, combination and relationship of the various parts disclosed in the specification, illustrated in the accompanying drawing, and set forth in the claims.

Figure 1 is a longitudinal elevation of a complete contactor attached to a trolley wire.

Figure 2 is a plan view of Figure 1.

Figure 3 is a vertical section along line 3—3 of Figure 1.

Figure 4 is a vertical section along line 4—4 of Figure 1.

Figure 5 is a vertical section along line 5—5 of Figure 1.

Figure 6 is a modification of Figure 3.

Numerals 10, 11 designate a pair of beams composed of insulating material, preferably wood, having a rectangular cross section, which beams are secured at each end thereof to a bracket 12 by bolts 13. These brackets have parallel faces 12A engaging the inner faces 10A, 11A, respectively, of beams 10, 11. These brackets are provided with a channel 14 for the reception of trolley wire 15, which wire is secured by clamp 16 secured by bolts 17. Numeral 16A designates a threaded hole for securing a bolt that may be desired for providing auxiliary support for the con-

tactor. It should be noted that this clamping arrangement provides for mounting the contactor on any straight section of wire, after cross bars 18 have been swung to their dotted positions, simply by raising the contactor for engagement of the channels 14 with the lower side of the wire; after the contactor has been elevated for attachment the end cross bars are swung to the full line position and secured by the bolts associated therewith, thus temporarily retaining the contactor on the wire while the operator locates and secures clamps 16 into locked position as shown in Figures 1 and 2. By this arrangement, a single individual can readily install the contactor without assistance.

Runway 19 is secured to ears 20—20, as a permanent sub-assembly 21 in any suitable manner such as swedging or welding. Four U shaped springs 22 are employed for yieldingly attaching the sub-assembly 21 to the beams. These springs embrace the preferably rounded ends of beams 10 and 11 and are secured thereto at their upper ends by bolts 23 which also serve as terminal posts for wires connecting the contactor to auxiliary electric devices referred to above. The lower ends of these springs are secured to laterally extending arms 20A—20A, of ears 20—20 by bolts 20B—20B. The ends of the runway are located in juxtaposed relation to the inner ends of webs 12B—12B depending from brackets 12—12.

It should be noted that the webs and the runway provide a substantially continuous under-run for depressing the trolley collector as it makes engagement and passes through the contactor.

It should also be noted that the beams of the contactor are disposed on each side of the trolley wire while the runway is directly below it, thus providing a balance between the forces of supporting the contactor and resisting the force applied thereto by the trolley collector. Incident to this passage, contacts 25, 26 are moved upwardly and forced into engagement with stationary contacts 27, 28. The latter contacts are attached to the lower ends of bolts 29, 30, while the former are fixed in yoke 19A secured to runway 19. These bolts 29, 29A and 30, 30A are disposed respectively, in beams 10, 11, and provide binding posts for attachment of wires leading to the accessory apparatus to be controlled by the engagement or disengagement of the contacts as the trolley collector passes through the trolley contactor and for securing cross bar 18 pivoted on bolt 30.

As an auxiliary means for centering and sup-

porting the runway during passage of the collector, the modified structure shown in Fig. 6 may be employed. In this embodiment yoke 19B carries contacts 25A, 26A disposed on an angle and co-acting with juxtaposed contacts 27A, 28A attached to bolts 29A, 30A.

It is to be understood that modifications of the present invention can be made without departing from the scope thereof and that only the claims herein express the limitations of my rights.

I claim:

1. A trolley contactor of the class described, comprising; two elongated beams composed of insulating material and disposed in parallel relation adjacent a trolley wire; means for attaching said beams to said wire in spaced relation thereto; a runway longitudinally disposed in parallel relation to said beams and adapted to operate a pair of electric contact members carried by the trolley contactor in response to pressure exerted by a trolley collector traversing said runway; and longitudinally disposed U shaped springs for attaching the runway to the beams, each spring having one end thereof attached adjacent the 25

jecting into the space between the arms of said spring, and the other end of each spring attached to an end of said runway.

2. In a device of the class described comprising, in combination, two elongated beams of insulating material fixedly secured one to the other in spaced relation to form a channel for receiving a trolley wire; means for attaching the beams to the trolley wire; a U-shaped spring at the end of each beam, each spring having one leg thereof lying substantially above the corresponding beam and fixedly secured thereto, and the other leg extending below the said corresponding beam with the U-portion of the spring extending over and around the corresponding end of the said corresponding beam; an elongated runway fixedly secured to the other leg of each spring and thereby flexibly supported by the said springs below the said beams; stationary contacts carried by the said beams, and a co-acting contact carried by the runway; and means operatively associated with each end of the said runway for guiding a current collector from the trolley wire onto the said runway.

FRANK H. RICHTERKESSING.
